UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,902, dated November 14, 1893.

Application filed October 9, 1893. Serial No. 487,668. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of rococo style of ornaments with sprays of flowers and 10 leaves running through said ornaments as represented in the accompanying drawing. In the center of said ornaments are fine lines forming small diamond shaped panels as shown. The border or upper portion of the 15 design is also formed of rococo style of ornaments with sprays of flowers and leaves springing from said ornaments as shown, with a narrow ornamental band separating the border from the hanging as shown in the drawing.

What I claim is—

1. The design for wall paper herein shown and described.
2. In the design for wall paper, the border herein shown and described.

Witness my hand this 5th day of October, 1893.

CHARLES BOOZE.
